UNITED STATES PATENT OFFICE.

HERMAN GUSTAVE MUELLERWEISS AND BRUCE EMERSON BRAUN, OF SEBEWAING,
MICHIGAN.

OIL-LEVEL INDICATOR.

1,407,670.

Specification of Letters Patent. Patented Feb. 21, 1922.

Application filed June 9, 1921. Serial No. 476,365.

To all whom it may concern:

Be it known that we, HERMAN G. MUELLERWEISS and BRUCE E. BRAUN, citizens of the United States, and residents of Sebewaing, in the county of Huron and State of Michigan, have invented certain new and useful Improvements in Oil-Level Indicators, of which the following is a specification.

10 An important object of this invention is to provide novel means whereby the oil level cock on an internal combustion engine may be readily opened from the dash board of the vehicle in which the internal combustion engine is arranged.

Further, the invention aims to provide an attachment of the class described capable of being applied to a motor vehicle either during the course of manufacture or at any 20 time thereafter without altering the construction of the vehicle.

Other objects and advantages will be apparent during the course of the following description.

25 In the accompanying drawing forming a part of this application and in which like numerals are employed to designate like parts throughout the same,

Figure 1 is a side elevation of the attachment applied.

Figure 2 is an end view of the engine transmission equipped with the attachment.

Figure 3 is a detail side elevation of the device connected to the oil level cock.

30 Figure 4 is a detail end elevation of a socket embodied in the invention, the socket being shown applied.

Figure 5 is a fragmentary perspective of a link forming a part of the invention.

40 In the drawing the numeral 5 designates an internal combustion engine of the type employed in the Ford automobile and which is provided with a transmission housing 6 having a detachable portion constituting a cover 7. The upper portion of the transmission housing and the lower portion of the cover 7 are provided with laterally projecting flanges 8 detachably connected in the usual manner by bolts 9.

50 As is well known, upper and lower cocks 10 and 11 respectively are threaded into the transmission and are provided with valves having heads 12 by means of which the valves may be rotated for opening the cocks.

55 The upper and lower cocks 10 and 11 are

periodically opened so that the level of the oil in the engine will be indicated by flowing out of one or both of the cocks. It is ordinarily a source of much inconvenience to the vehicle operator to be required to get beneath the car to operate the cocks 10 and 11 and we have therefore provided means whereby the upper cock 10 which is the principal oil level indicating medium may be opened and closed from the dash board. 60 An operating rod generally designated by the numeral 16 is bent intermediate its ends to form long and short branches 17 and 18 respectively.

The long branch 17 is rotatably extended 70 through a bearing plate 20 attached to the transmission housing by means of one of the bolts 9. In attaching the bearing plate 20 it is merely necessary to remove one of the bolts 9 and subsequently extend the bolt 75 through the bearing plate and the flanges 8.

The short branch 18 of the operating rod 16 is provided with a depending terminal portion 21 rotatably extended through an eye 24 formed at the forward end of a link 80 25. The link when applied is inclined downwardly toward its forward end and extended through the dashboard 26 and a bearing plate 27 attached to the dash board. Stop elements 28 in the nature of cotter keys are 85 extended through the link 25 on opposite sides of the dash and serve to limit the end-wise movement of the link whereby the rotation of the valve of the cock 10 is limited. The rear terminal portion of the link 25 is 90 extended laterally to define a handle 30 by means of which the link 30 may be drawn either forwardly or rearwardly.

As illustrated in Figures 3 and 4, the lower end of the branch 17 is formed with a socket 95 32 having spaced sides 33 with which the head 12 is engaged. The side walls 33 are provided adjacent their ends with incisions 34 which define fingers 36, the said fingers being bent inwardly to engage the under 100 sides of the head 12 whereby to hold the socket 32 in engagement with the head.

In operation the device is applied in the manner illustrated in Figure 1 and when it is desired to open the cock 10 it is merely 105 necessary to draw the link 25 rearwardly whereupon the operating rod 16 will be rotated in a clockwise direction for imparting a quarter turn to the head 12 and the valve connected thereto. As previously stated the 110

stop elements 28 limit the endwise movement of the link 25 so that the rotation of the valve in the cock 10 is limited. The stop elements 28 also serve as a means for holding 5 the link 25 in position.

As the link 25 is inclined downwardly toward the laterally projecting branch 16 it tends to rotate the operating rod 16 in an anti clockwise direction so that the vibration of the vehicle will not cause the 10 accidental endwise movement of the link 25 for operating the cock.

Having thus described the invention, what is claimed is:—

- 15 1. An attachment for internal combustion engines comprising a rod having a bend defining a pair of branches extending angularly with relation to each other, one of the branches being formed with a socket 20 adapted for connection with the oil indicating cock of an internal combustion engine, a link connected to the other branch, and means associated with said link to limit the endwise movement of the same.
- 25 2. The combination with an internal combustion engine having an oil level indicating cock, of a rod having a bend defining upper and lower branches, the lower branch being formed with a socket having connection with said cock, and a link connected to the upper branch of said rod, said link being provided with spaced stop elements limiting its endwise movement and with a lat- 30

erally projecting terminal portion defining a handle.

3. The combination with an internal combustion engine having an oil level indicating cock, of a rod having a bend defining upper and lower branches extended angularly with relation to each other, the lower branch being provided with a socket connected to said cock, a longitudinally movable downwardly inclined link having its forward end formed with an eye receiving the upper branch of said rod, a pair of 45 spaced cotter keys extended through said link to limit the endwise movement of the same, said link being extended through the dashboard of the vehicle to which the engine is attached and provided with a laterally projecting terminal portion defining a handle, said link being downwardly inclined toward said rod whereby the cock is normally held in its closed position.

4. An attachment for internal combustion 55 engines comprising a rod having a pair of branches, one of which is provided with means for engaging the oil indicating cock of an internal combustion engine, a link connected to the other branch, and means 60 associated with said link to limit the longitudinal movement of the same and thereby limit the movement of the rod.

HERMAN GUSTAVE MUELLERWEISS,
BRUCE EMERSON BRAUN.
